(57) **CLAIM**

The ornamental design for a vehicle tire tread, as shown and described.

DESCRIPTION

FIG. 1 is an outside perspective view of a vehicle tire tread showing our design, it being understood that the depicted tread pattern extends over the entire circumference of the tire;

FIG. 2 is front elevational view thereof;

FIG. 3 is a rear elevational view thereof;

FIG. 4 is an outside elevational view thereof;

FIG. 5 is an inside elevational view thereof;

FIG. 6 is a top view thereof;

FIG. 7 is a bottom view thereof;

FIG. 8 is an outside perspective view of a second embodiment of the vehicle tire tread design shown in FIGS. 1-7; and,

FIG. 9 is an inside perspective view of the second embodiment of the vehicle tire tread design shown in FIG. 8.

In the drawing figures, the tire features shown in broken lines indicate environmental subject matter only, and form no part of the claimed design.
